HYDRAULIC PUMP

Poul Haahr, Copenhagen, Denmark

Application May 21, 1947, Serial No. 749,434
In Denmark February 9, 1946Section 1, Public Law 690, August 8, 1946
Patent expires February 9, 1966

6 Claims. (Cl. 103—11)

1

The present invention relates to arrangements in hydraulic presses of the type having a low-pressure pump and a high-pressure pump.

My invention especially relates to arrangements of the kind in which are provided means for utilizing the low-pressure pump as a feeding pump for the high-pressure pump.

In arrangements of the kind described above, a spring loaded valve is provided for discharging the excess fluid from the low-pressure pump when operating as feeding pump for the high-pressure pump.

It is the main object of my invention to provide an improvement of the arrangement of the kind referred to in which the efficiency can be increased compared with the known arrangements.

A further object of my invention is to provide improvements in which an increased efficiency can be obtained by means of a simple and reliable construction.

The invention is illustrated in the drawing in which

Fig. 1 is a schematical view of the pipe line connections in a press including a valve device in accordance with this invention and

Fig. 2 is an enlarged section of the valve device.

In Fig. 1, 4 denotes a low-pressure pump which may be a gear pump and 5 is a high-pressure pump.

The driving shafts of these pumps are mechanically coupled by means of a coupling 6 and are driven in any convenient manner. These pumps serve to generate pressure fluid for a hydraulic press cylinder the piston of which is denoted by 3. The press cylinder 2 is by means of pipe lines 12 and 13 connected with a reversing valve 11 through which pressure fluid can be supplied either to the upper side or the lower side of the press piston 3, as the case may be. The inlet of the reversing valve 11 is by means of the pipe line 14 connected with a valve device 15, the details of which will be apparent from Fig. 2.

The pipe line 14 communicates inside the valve device 15 with a space 16 communicating in its turn through a non-return valve 17 with another space 18. The non-return valve 17 is normally held in its closed position by means of a spring 19 and its lift is limited by an abutment 20. The space 18 communicates directly with the delivery side of the low-pressure pump 4 and communicates further through a non-return valve 21 with a return line 22 to the fluid reservoir (not shown) of the press plant. The non-return valve 21 is loaded by a relatively heavy spring 23 the ten-

2

sion of which can be varied by a bushing 24 constituting abutment for the spring 23 being screwed to or from a case 25 enclosing the non-return valve and its spring. Obviously the tension of the spring 23 determines the pressure at the delivery side of the low-pressure pump, as the non-return valve will be lifted so as to connect the delivery side of the low-pressure pump with the return lines 22 when the said pressure will have attained a certain value.

As will be apparent from Fig. 1 the space 18 also communicates through a pipe line 26 with the inlet of the high-pressure pump 5. The delivery side of this pump communicates through a pipe line 27 with the space 16 in the valve device 15. The non-return valve 21 abuts as shown in Fig. 2 against one end of a piston 28 which is slidably mounted in a cylinder 29 communicating through a pipe line 30 with the pipe line 14. A pipe line 31 communicating with a low-pressure manometer (not shown) opens into the space 18 in the valve device 15 and a pipe line 32 connects the space 16 of the valve device with a high-pressure manometer (not shown).

25 A control valve 33 is inserted in the pipe line 13 and serves to control an ejector 9 for ejecting the work after it has been acted on by the press.

The press plant described operates as follows. It is assumed that the press piston 3 is in its uppermost position and the pumps 4 and 5 are in operation. Pressure fluid will then flow from the low-pressure pump 4 into the space 18 in the valve device 15 and from there pass through the non-return valve 17 to the said space 16. It will be realized that the high-pressure pump will thus effect no substantial work, the pressure difference between the spaces 18 and 16 of the valve device 15 being very small. From the space 16 of the valve device 15 pressure fluid will flow through the line 14 to the control slide 11 and from the latter through a return line 43 back to the fluid reservoir of the plant. The pressure in the line 14 and consequently in the space 16 will thus be quite small and the low-pressure pump 4, therefore, effects no substantial work, i. e. both the low-pressure pump 4 and the high-pressure pump 5 will idle.

If now the control slide 11 is displaced in such a manner as to provide connections in the first 50 hand between the line 14 and the line 12 and furthermore between the line 13 and the return line 43 the pressure fluid supplied through the line 14 will be fed to the upper side of the press piston 3, the fluid below the piston being at the 55 same time allowed to escape through the return

line 43. The piston 3 will therefore move downwards until it will meet resistance. Hereby the pressure in the pipe lines 12 and 14 is increased at the same time as the flow of fluid is substantially stopped. Hereby the non-return valve 17 of the valve device 15 is closed and the fluid supplied from the low-pressure pump 4 now flows exclusively from the space 18 through the pipe line 23 to the high-pressure pump 5 which with an increased pressure feeds the fluid into the space 16 and from there into the pipe line 14. From here the pressure fluid will flow through the line 33 to the cylinder 29 whereby the piston 28 will be capable of lifting the valve 21 against the action of the spring 23 until the valve abuts against an adjustable abutment 44. The space 18 of the valve device 15 will thus communicate with the return line 22 whereby the pressure in the space 18 diminishes to the value determined by the lift of the valve 21. The abutment 44 determining this lift is adjusted in advance in such a manner that the pressure in the space 18 will be sufficient to provide for the necessary feeding of the high-pressure pump 5. The low-pressure pump 4 will thus operate against a smaller counter-pressure while the high-pressure pump 5 takes over the essential part of the work. The pressure in the pipe line 14 and consequently in the press cylinder 2 is now increased in the course of a very short time, e. g. $\frac{1}{2}$ second, to the maximum value determined by a safety valve (not shown) whereby the press acts upon the object placed therein. If now the control slide 11 is displaced the pipe line 12 will be connected with an outlet 45, while the pipe line 14 will be connected with the pipe line 13. Hereby the pressure in the pipe line 14 will act upon the lower side of the piston 3 which will consequently be lifted without making any substantial resistance. The pressure in the pipe line 14 will therefore decrease correspondingly which permits the spring 23 to close the valve 21 again. The pressure in the delivery pipe 27 of the high-pressure pump 5 decreasing at the same time to the same extent as the pressure in the pipe line 14, the pressure in the space 18 will be greater than that in the space 16, i. e. the low-pressure pump 4 now takes the whole work of lifting the piston 3. When the latter will be attained its uppermost position it will be stopped and the pressure will now increase in the pipe line 13 as well as in the pipe line 14 which would involve actuation of the high-pressure pump if no special measures were taken to prevent this. In the example shown these measures comprise the provision of a non-return valve 46 in the piston 3 through which the space below the piston is allowed to communicate with the space above the piston in its turn communicating through the pipe line 12 with the outlet 45. Such safety valve may, however, also be arranged direct in the pipe lines 16. In both cases the load on the valve should be such that the valve will open in response to a smaller pressure than that required for lifting the valve 21 of the valve device 15.

I claim:

1. An arrangement of the kind referred to comprising a low-pressure pump and a high-pressure pump; means for feeding the high-pressure pump from the low-pressure pump; an automatic spring-loaded valve for discharging the excess fluid from the low-pressure pump when operating as feeding pump for the high-pressure pump; supplementary means for operating said valve under the influence of the pres-

sure at the delivery side of said high-pressure pump; and an abutment determining the maximum lift of said valve.

5 2. An arrangement of the kind referred to comprising a low-pressure pump and a high-pressure pump; means for feeding the high-pressure pump from the low-pressure pump; an automatic spring-loaded valve for discharging the excess fluid from the low-pressure pump when operating as feeding pump for the high-pressure pump; a piston for operating said valve under the influence of the pressure at the delivery side of said high-pressure pump; and an abutment determining the maximum lift of said valve.

10 3. An arrangement of the kind referred to comprising a low-pressure pump and a high-pressure pump; means for feeding the high-pressure pump from the low-pressure pump; an automatic spring-loaded valve for discharging the excess fluid from the low-pressure pump when operating as feeding pump for the high-pressure pump; a piston for operating said valve under the influence of the pressure at the delivery side of said high-pressure pump; an abutment determining the maximum lift of said valve; and means for subjecting said piston to the pressure in the feeding duct of the press when the low pressure pump operates as feeding pump for the high-pressure pump.

15 4. An arrangement of the kind referred to comprising a low-pressure pump and a high-pressure pump; means for feeding the high-pressure pump from the low-pressure pump; an automatic spring loaded valve for discharging the excess fluid from the low-pressure pump when operating as feeding pump for the high-pressure pump; a piston for operating said valve under the influence of the pressure at the delivery side of said high-pressure pump; an abutment determining the maximum lift of said valve; and automatic means for subjecting said piston to the pressure in the feeding duct of the press when the low-pressure pump operates as feeding pump for the high-pressure pump.

20 5. An arrangement of the kind referred to comprising a low-pressure pump and a high-pressure pump; means for feeding the high-pressure pump from the low-pressure pump; an automatic spring loaded valve for discharging the excess fluid from the low-pressure pump when operating as feeding pump for the high-pressure pump; a piston for operating said valve under the influence of the pressure at the delivery side of said high-pressure pump; an adjustable abutment determining the maximum lift of said valve; and automatic means for subjecting said piston to the pressure in the feeding duct of the press when the low-pressure pump operates as feeding pump for the high-pressure pump.

25 6. In and for hydraulic presses, a low-pressure pump; a high-pressure pump; an automatic valve device comprising a spring loaded check valve for determining the delivery pressure of said low-pressure pump; means responsive to pressure at the delivery side of said high-pressure pump to lift said check valve; means determining the lift of said check valve, said valve being movable independently of said lifting means under the action of pressure acting on it; means connecting the delivery side of said low-pressure pump with the inlet of said high-pressure pump; means connecting the delivery side of said low-pressure pump with the delivery side of said high-pressure pump; and means in said last named connection

for closing the same at a certain pressure prevailing at the delivery side of the high-pressure pump.
